UNITED STATES PATENT OFFICE.

RAYMOND D'EQUEVILLEY-MONTJUSTIN, OF KIEL, GERMANY.

SUBMARINE BOAT.

943,604.

Specification of Letters Patent. Patented Dec. 14, 1909.

Application filed May 12, 1908. Serial No. 432,547.

To all whom it may concern:

Be it known that I, RAYMOND D'EQUEVILLEY-MONTJUSTIN, a subject of the King of Spain, and a resident of Kiel, in the Empire of Germany, have invented certain new and useful Improvements in Submarine Boats, of which the following is a specification.

The present invention relates to submarine boats.

In order to make it possible for submarine boats to dive from their position of rest in a vertical direction, so-called vertical propellers are employed, that is, propellers mounted on vertical shafts. These vertical propellers are either arranged in the middle of the boat or at both ends of the boat at equal distances from the middle of the boat. In the latter instance the vertical propellers are generally arranged in conduits or shafts which project vertically through the boat. When such vertical propellers are employed vertically directed end-thrusts take place which, when the engine driving the propellers is started, suddenly increase from zero to their maximum and therefore act with a shock on the boat. Practical experiments with such vertical propellers have therefore demonstrated that they act too violently on the boat. Furthermore, it has been demonstrated that with vertical propellers arranged at the ends of the boat it is extremely difficult to drive the two propellers with the same number of revolutions. When such vertical propellers are used there is therefore danger of causing disastrous disturbances to take place relating to the equilibrium of the boat.

The object of the invention is to remedy these drawbacks.

Two embodiments of the invention are shown in the accompanying drawings, by way of example.

Figure 1 shows one embodiment of a submarine boat in vertical longitudinal section; Fig. 2 is a vertical section through the middle of the boat; Fig. 3 is a view corresponding to Fig. 2, but showing a slightly different embodiment of the invention, and Fig. 4 is a longitudinal horizontal section of the embodiment shown in Fig. 1.

On the top and in the middle of the boat is arranged a conning tower *k* which communicates with the compartment *a* for the

crew. Entrance-hatches *e* are provided at 55 both sides of the tower *k*.

According to Figs. 1, 2 and 4 of the drawings the diving device of the boat consists of two separate suction-pipes *s* which are mounted in the compartment *a* below the center of buoyancy of the entire boat. Each pipe *s* extends first vertically from the bottom of the boat and then horizontally or approximately horizontally to the sides of the boat. A turbine-propeller or screw-propeller *o*, *p* is arranged in the horizontal part *t* of each pipe. The propellers *o*, *p* are mounted directly on the shaft *n* of the motor *m* arranged intermediate of the propellers. The blades of one propeller are directed oppositely to those of the other propeller in such a manner that when the propellers turn in one direction the outside water is drawn in through the lower mouth of the pipes *s* and expelled through the mouth of the part *t* of the pipes and, when the propellers turn in the opposite direction the outside water is drawn in through the mouth of the part *t* of the pipes and is expelled downwardly through the vertical pipes *s*. The shaft *n* projects through the wall of the part *t* of the pipes in a watertight manner. It is unnecessary to provide special bearings as the axial thrusts of the two propellers *o*, *p* counterbalance one another.

According to Fig. 3 the diving device of the boat consists of a single vertical suction-pipe which below the motor *m* is divided into two horizontal pipe-portions *t* which open toward the sides of the boat. The arrangement of the propellers *o*, *p* is similar to that of the embodiment shown in Fig. 2. The front part of the boat is also provided with a suction-pipe whose lower, vertical part merges into a horizontal part *r* which has two branches *w* opening into the sides of the boat. In the horizontal part *r* of the suction-pipe is arranged a propeller *v* whose shaft can be driven directly in both directions by a motor *u* arranged in the compartment *a* for the crew.

The mode of operation of the diving device is as follows: During the surface-travel the boat floats on the draft-line *L*—*L*, the ballast-compartments being partially or completely emptied. When the ballast-compartments are filled the boat floats on the

draft-line M—M and is ready to dive. The boat then still has a small excess of buoyancy which corresponds to the volumes of the conning tower *k* and hatches *e*. When it is desired to cause the boat to dive the propellers *o*, *p* are rotated by means of the motor *m* so as to cause the outside water to be drawn in through the lower openings of the vertical pipes *s* and expelled through the horizontal pipe-portions *t*. This causes the pressure to become decreased at the lower openings of the suction-pipes *s* and the decrease in pressure causes the boat to dive. The boat continues to sink for as long a time as the suction-effect of the propellers *o*, *p* is greater than the effect of the excess of buoyancy. If the boat is to be maintained at a certain depth it suffices to keep the propellers rotating at a speed which causes the suction-effect to become equal to the effect of the excess of buoyancy. If the propellers *o*, *p* are rotated in the direction opposite to that in which they were rotated during the diving, an excess of pressure, instead of a decreased pressure, is created at the lower openings of the suction-pipes *s* which causes the boat to rise rapidly.

The suction-device in the front part of the boat is used for changing the longitudinal inclination of the boat. By rotating the propeller *v* at a greater or less speed and in one direction or the other any desired inclination may be imparted to the longitudinal axis of the boat by means of this suction-device. The bearing-pressure or thrust in the direction of the shaft of the propeller, which is caused to take place by the rotation of the propeller *v*, is absorbed by the body of the boat and does not influence the position of equilibrium of the boat.

As compared with the vertical propellers already mentioned the diving device according to the present invention presents the advantage of causing the diving to take place smoothly and without shocks because the thrusts or bearing-pressures created by the starting of the propellers *o*, *p* act transversely to the direction of diving of the boat, that is they are without influence on the diving, and because, when the propellers are started, the circulation effecting the diving takes place gradually. Furthermore, the special shape of the suction-pipes *s*, *t* permits of the diving device being arranged in the middle of the boat below the conning tower, as there is sufficient free space left above the suction-pipes by reason of the curved formation of the pipes. Vertical propellers operating in vertical shafts do not permit of such arrangement of the diving device. The suction-device *r w v* might also be arranged in the rear part of the boat and might be of the same construction as the diving device *s*, *t*, *o*, *p*. The shafts of the propellers *o*, *p* and *v* might also be inclined

a little toward the horizontal plane. Furthermore, the diving device might have only one propeller, in which case the device may be of a construction similar to that of the suction-device *r w v*.

Any suitable member which is capable of creating a circulation in the suction-pipes may be employed in lieu of the propellers *o*, *p*, *v*.

Having thus described the invention, what is claimed and desired to be secured by Letters Patent is:—

1. A submarine boat having a conduit in communication with the outer water and through which water is made to circulate to develop the diving action, the lower portion of said conduit leading in a substantially vertical direction from the bottom of the boat, and means causing a flow of water through said conduit, acting upon the water within said conduit in a direction substantially transverse to the diving direction whereby the reaction of said means is not exerted in a direction to influence the diving action.

2. A submarine boat having a conduit communicating with the outer water, the lower portion of said conduit extending vertically from the bottom of the boat, and the upper portion of said conduit terminating in opposed horizontally presented openings at the sides of the boat, and means for causing a circulation through the conduit, acting upon the water therein in a direction substantially transverse to the diving direction whereby the reaction of said means is exerted in a direction that does not influence the diving action.

3. A submarine boat having a conduit communicating with the outer water and through which the water is caused to circulate in developing the diving action of the boat, said conduit extending for a portion of its length vertically from the bottom of the boat and for a portion of the way in a substantially horizontal direction, terminating in two opposed openings presented in a substantially horizontal direction at the sides of the boat, and two opposed means acting upon the water in the conduit, in a direction substantially transverse to the diving direction, whereby the reactions of said means not only take place in a direction that does not affect the diving operation but are balanced.

4. In a submarine boat, a conduit communicating with the outer water and through which the water is made to circulate in developing the diving action of the boat; said conduit extending in part in a substantially vertical direction from the bottom of the boat and in part in a substantially horizontal direction and terminating in two opposed openings presented in a substantially horizontal direction at the sides of the boat;

and means in the horizontal portion of the conduit, acting upon the water therein in a direction substantially transverse to the direction of diving and thereby presenting its 5 reaction against the boat in a direction that does not affect the diving.

5. In a submarine boat, a conduit through which water is caused to flow in developing the diving or counter-diving action of the 10 boat; said conduit communicating with the outer water through a plurality of openings in the bottom of the boat and extending in part vertically from the bottom openings and in part in a substantially horizontal di- 15 rection and terminating in opposed laterally presented openings through which it communicates with the outer water at the sides of the boat and a plurality of means reacting against one another, acting upon 20 the water in the horizontal portions of the conduit, and in a direction substantially transverse to the diving direction.

6. In a submarine boat a conduit through which water is caused to circulate in affecting 25 the diving direction of the boat; said conduit extending in part vertically from the bottom of the boat and having two oppositely extending substantially horizontal portions terminating in openings at the 30 sides of the boat, means located in the horizontal portions of the conduit, acting upon the water therein in opposed horizontal directions, whereby their reactions are balanced and having a common driving means 35 whereby their actions upon the water are equal.

7. A submarine boat having a plurality of conduits through which water is caused to circulate in developing the diving action; each of said conduits extending in part vertically from the bottom of the boat and in part in a substantially horizontal direction terminating in two opposed laterally presented openings; the horizontal portion of one of said conduits extending transversely 40 of the boat and the horizontal portion of the other conduit extending in part longitudinally of the boat; each of said conduits being provided with means acting on the water in the horizontal portions, in a sub- 45 stantially horizontal direction, to develop the flow of water through the conduits.

8. In a submarine boat, a conduit communicating with the water at the bottom of the boat and extending in part vertically from 50 the bottom of the boat, in part horizontally and longitudinally of the boat and in part horizontally and transversely of the boat and terminating in opposed laterally presented openings communicating with the 55 outer water at the sides of the boat; and means in a horizontal portion of said conduit acting upon the water therein in a direction substantially horizontal.

The foregoing specification signed at 60 Kiel, Germany, this 26th (twenty-sixth) day of March, 1908.

RAYMOND D'EQUEVILLEY-MONTJUSTIN.
